DESIGN FOR A TOOLHOLDER

Herman C. Muhlbach, Los Angeles, and Michael L. Wesley, Pasadena, Calif.

Application October 30, 1944, Serial No. 116,065

Term of patent 3½ years

(Cl. D93—4)

To all whom it may concern:

Be it known that we, Herman C. Muhlbach and Michael L. Wesley, are both citizens of the United States of America and residents of the city of Los Angeles and Pasadena, respectively, in the State of California, and have invented a new, original, and ornamental Design for a Toolholder, of which the following is a specification, reference being had to the accompanying drawing forming part thereof.

In the drawing:

Figure 1 is an elevational view of a toolholder showing my new design,

Figure 2 is a bottom plan view, and

Figure 3 is a top view.

We claim:

The ornamental design for a toolholder, substantially as shown.

HERMAN C. MUHLBACH.

MICHAEL L. WESLEY.
